UNITED STATES PATENT OFFICE.

JOHN B. LAMBE, OF GRAETTINGER, IOWA.

PIPE-CUTTER.

1,270,175.

Specification of Letters Patent. Patented June 18, 1918.

Application filed July 30, 1917. Serial No. 183,569.

To all whom it may concern:

Be it known that I, JOHN B. LAMBE, a citizen of the United States of America, residing at Graettinger, in the county of Palo Alto and State of Iowa, have invented new and useful Improvements in Pipe-Cutters, of which the following is a specification.

The present invention has reference generally to improvements in that class of inventions known as cutting and punching and more particularly relates to a pipe cutter.

It is the primary aim and object of this invention to provide a device of the above character designed for removably receiving a section of pipe so as to hold the latter in a proper position during the operation of the cutting means for severing the pipe into two smaller sections or nipples.

More particularly, this invention aims to provide a pipe cutter wherein the construction thereof permits of the removable supporting of a pipe section beneath the cutting means so as to assure of a quick and effective cutting of the pipe section, the cutting means being designed to pass between the pipe receiving and supporting means.

It is a more specific object of this invention to provide a pipe cutter wherein the pipe section receiving sleeves are expandable so as to assure of an effective engagement of the pipe section on the sleeves preparatory to the cutting operation.

As a further improvement the present invention embraces the provision of a pipe cutter wherein common means is provided for supporting and guiding the cutter during movement and for also supporting the pipe section when in position on the sleeves.

Among the other aims and objects of this invention may be recited the provision of a device of the character described with a view to compactness, and in which the number of parts are few, the construction simple, the cost of production low and the efficiency high.

Other improvements and novel details in the construction and arrangement of the various parts of the apparatus will be brought out more in detail in the description to follow which for a clear understanding of the invention should be considered in connection with the accompanying drawings forming a part hereof, and wherein is disclosed for the purpose of illustration, a convenient and satisfactory embodiment of

the invention. It is to be noted in this connection that minor changes in the construction and arrangement of parts may be made without departing from the principle of 60 operation of the various parts.

The invention is clearly illustrated in the accompanying drawings in which:—

Figure 1 is a top plan view of the device; Fig. 2 is a front elevation thereof; 65

Fig. 3 is an end elevation of the invention;

Fig. 4 is an enlarged fragmentary longitudinal sectional detail;

Fig. 5 is a detail of the invention. 70

Similar characters of reference are employed in all the above described views, to indicate corresponding parts.

Referring now, more particularly, to the accompanying drawings, there is provided a 75 supporting base plate 1 being relatively flat and of a rectangular configuration while mounted on the upper surface of the base plate is the improved pipe section receiving means which, in the present instance, may be 80 said to consist of a pair of relatively long rods 2 the outer ends of which are bent angularly as at 3 and rigidly connected to the upper surface of the plate 1 adjacent one edge thereof while portions of the rod are 85 offset as at 4 and arranged in substantially spaced parallel relation the free ends thereof being rigidly secured to an expandible pipe receiving sleeve 6 the latter being slit as at 7 to allow expansion of the sleeve in a manner 90 that will hereinafter become apparent. Relatively short rods 8 are now employed and have ears 9 formed on their angularly bent ends 10 while the ears are in turn pivotally mounted through the instrumentality of suit- 95 able pintles 11 between pairs of spaced ears 12 carried on opposite surfaces of the plate 1 adjacent the opposite end. Another expandible pipe receiving sleeve 13 is rigidly connected to the outer ends of the rods 8 and 100 is of a construction similar to the construction of sleeve 6 being slit as at 14 to allow expansion.

As intimated, improved means have been provided for expanding the sleeves. In reducing this feature of the invention to practice in each sleeve opposed and oppositely threaded rods 15 are rigidly connected at their outer ends to diametrically opposite points on the inner surface of each sleeve 110 while the adjusting sleeve 16 has its inner surface adjacent its opposite ends threaded

correspondingly to the free ends of the rods 15 which are adjustably arranged within the sleeve 16 as indicated. A cog wheel 17 is carried intermediate the ends of the sleeves 6 and is adjustably engageable by a rack bar 18, the handle 19 of which is slidably mounted in suitable bearings 20 carried adjacent the outer edge of each sleeve as indicated. A knob 21 is formed on the outer 10 end of the handle and as is apparent by adjusting the knob owing to the arrangement of the rack bar 18 and the cog wheel 17 the sleeve 16 will be rotated and by reason of the engagement of the rods 15 with the sleeve it is apparent that the pipe section receiving sleeves 6 and 13 will be readily expanded and contracted. This expanding action of course occurs subsequent to the arrangement of a pipe section on the sleeves. 15

20 Coöperating with the pipe receiving sleeves is the improved common means for supporting the pipe section when it is disposed on the sleeves and for supporting and guiding the operation of the cutting means. In accomplishing this purpose, opposed bars 22 are arranged transversely of the plate 1 at points beneath the outer edges of the sleeves 6 and 13 and of course are arranged in closely spaced parallel relation 25 with respect to each other. These bars are provided intermediate their ends with alining arcuate recesses 23 while supporting posts or standards 24 are formed adjacent one of the ends of the bars for pivotally supporting the cutting means which 30 may be said to consist of a blade 25 in one edge from the inner edge and adjacent the upper end of which projects a lug 26 pivotally mounted through the instrumentality 35 of suitable fastening devices 27 between the upper ends of the posts 24 while a handle 40 extends from the opposite end and adjacent the upper edge of the blade, as indicated. Upright guides 29 are formed on 45 the opposite ends of the bars 22 and are arranged in opposed and spaced relation with 50 respect to each other so as to guide the movement of the cutting blade 25 as it is moved downwardly across the pipe section 30.

The mode of operation of the present invention may be reviewed as follows:—

Assuming that the parts have been assembled in the manner described and as indicated in the drawings, to apply a section 55 of pipe 30 and sever the same into two sections or nipples the rods 8 carrying the sleeve 13 are swung upwardly to permit of the application of pipe section 30 over the sleeve 6 and the portions 4 of the rods 2 so 60 that the pipe section 30 may be entirely arranged on these parts and permit of the swinging of the rods in the sleeve 13 to their original position. Subsequent to this 65 action the pipe section 30 is slid over the

sleeve 13. Now, as soon as the pipe section has been properly adjusted on these sleeves the knobs 21 may be actuated so that the rack bars will rotate the cog wheels 17 to consequently expand the sleeves so as to 70 assure of the effective engagement of the sleeves with the pipe section. In this connection it is to be observed that the pipe section rests in the recesses 23 in the bars. The parts are now in the proper position for 75 the operation of the cutting means. The handle 28 is grasped so as to swing the blade 25 about its pivot while the cutting edge of the blade will engage the pipe section and sever it during the continued 80 downward movement of the handle, the blade being guided during such movement between the guides 29 and by reason of the fact that the adjacent edges of the sleeves are arranged in spaced relation with each 85 other the blade will readily pass between the space while cutting the pipe section 30.

It is believed that in view of the foregoing description a further detailed description of the operation of the invention 90 is entirely unnecessary. Likewise it is believed that the advantages of the invention will be readily apparent.

Having thus fully described the invention what is claimed as new and desired to 95 be secured by Letters Patent is:—

1. A device of the character described including a supporting base plate, a rigidly mounted pipe receiving sleeve on the base plate, a movably mounted pipe receiving 100 sleeve on the base plate arranged in alinement and in spaced relation with the first sleeve, cutting means, and common means mounted on the base plate and positioned beneath the pipe section receiving sleeve so 105 as to support the latter in spaced relation to the plate and being also designed to pivotally support the cutting means in guiding movement thereof when swung downwardly so as to pass between the 110 sleeves.

2. A device of the character described including a supporting base plate, a pair of expansible pipe receiving sleeves mounted on the base plate one of which is movable 115 relative to the other, means on the base plate and positioned beneath the adjacent spaced edges of the sleeves for supporting the sleeves in spaced relation to the base plate, and cutting means pivotally mounted 120 with respect to the base plate and adapted to sever a pipe section mounted on the sleeves and passed between the sleeves.

3. A device of the character described including a base plate, a pair of split pipe receiving sleeves mounted on the base plate one of which is movable relative to the other, oppositely threaded rods carried at diametrically opposite points on the inner surface of each sleeve, an adjusting sleeve 125

operably mounted on the adjacent ends of the opposed rods, a cog wheel carried by the sleeve, a manually operable rack bar slidably mounted in each sleeve and engageable with the adjacent cog wheel for expanding and contracting each sleeve, means on the base plate for supporting the adjacent spaced edges of the sleeves, and cutting means operably mounted on the base plate 10 and designed for movement between the adjacent edges of the sleeves when cutting a section of pipe on the sleeves.

4. A device of the character described including a supporting base plate, spaced 15 transversely arranged bars on the base plate provided with recesses in their upper edges and intermediate their ends, posts formed on the inner ends of the bars, a cutter pivotally mounted on the upper ends of the posts,

cutter guides formed on the opposite ends 20 of the bars, a pipe supporting sleeve, a pair of rods having their outer ends connected to the base plate and having portions thereof offset and connected at their free ends to the inner ends of the sleeve so as to 25 maintain the outer end of the sleeve above the recesses in the adjacent cross bar, another sleeve, and supporting rods therefor having their inner ends pivotally connected to the opposite end of the base plate and 30 their opposite ends connected to the adjacent end of the last mentioned sleeve so as to dispose the outer edge of the sleeve above the recess in the adjacent transverse bar, substantially as described. 35

In testimony whereof I affix by signature.

JOHN B. LAMBE.
